UNITED STATES PATENT OFFICE.

FRANK W. LINDSLEY, OF JERSEY CITY, NEW JERSEY.

HORSESHOE.

No. 829,114.

Specification of Letters Patent.

Patented Aug. 21, 1906.

Application filed March 8, 1906. Serial No. 304,948.

To all whom it may concern:

Be it known that I, FRANK W. LINDSLEY, a citizen of the United States, and a resident of Jersey City, in the county of Hudson and State of New Jersey, have invented certain new and useful Improvements in Horseshoes, of which the following is a specification.

My invention relates to horseshoes, and has for its object to provide means whereby the driver may readily and quickly adjust points or calks of shoe to sharpen same and prevent horse from slipping on smooth or icy roads and pavements and at the same time provide a spring-cushion tread.

My invention consists, essentially, of a horseshoe having a toe-calk provided with adjustable toe-points affording a spring-cushion tread and heel-calks provided with adjustable heel-points, said toe and heel points being so devised that they may be readily and quickly adjusted by the driver when needed.

The nature of my invention will be best understood when described in connection with the accompanying drawings, in which—

Figure 1 is a lower face view of my improved horseshoe. Fig. 2 is a section on the line 22, Fig. 1. Fig. 3 is a view of part of the upper face. Fig. 4 is an end view of Fig. 3. Fig. 5 is a plan view of the toe-calk.

Similar characters of reference designate corresponding parts throughout the several views.

In the drawings, 10 indicates the horseshoe proper, 11 the heel-calks, and 12 the toe-calks. The heel-calks 11 may be formed in the usual manner or may consist of separate steel blocks welded or screwed to the shoe 10. The toe-calk consists of a steel bar with specially-formed ends 13 and an intermediate curved bearing portion 14. This calk is riveted or screwed to the shoe 10. The heel-calks 11, as well as the ends 13 of the toe-calk 12, are tapped and closely threaded to receive screw-points 15, which are made to pass through the said calks and project above and beneath said shoe, as shown. These screw-points may be further secured by suitable set-screws, if desired. The part of the screw-point projecting beneath the shoe serves to sharpen said shoe, thereby preventing a horse from slipping, &c. The portion projecting above the said shoe is adapted to receive a key or wrench whereby it may be

turned, thus lowering or raising the said screw-point to suit the occasion. I prefer to make the said screw-points 15 of steel and of substantially the form shown in the drawings, with three equally-spaced longitudinal grooves. A screw-thread is cut upon the said screw-points throughout their entire length, and their centers are hardened more than the exterior, so that they will wear substantially to points. These screw-points, as stated, pass through the calks and shoe and are made to pass through at an angle conforming with the hoof 16. Between the two ends 13 of the toe-calk 12 is an adjustable series of intermediate points 16 upon the lateral edge of a substantially semicylindrical transversely grooved or corrugated plate 17, the points being formed and kept sharp by the wearing of said corrugations. The corrugations are made farther apart on one lateral edge than on the other, forming blunter and stiffer points, so that by reversing said plate a different degree of sharpness and spring may be obtained. This plate 17 bears against and is supported by the surface, curved to conform with said plate, of the intermediate curved bearing portion of the toe-calk 12 and is fastened thereto by means of the tap bolts or screws 18. These bolts or screws pass through the slots 19 in the plate 17, and their shanks 20 are beveled to fit the notches 21 of said slots, so that by screwing down these bolts or screws 18 sufficiently the plate will be confined to the particular notch desired. I have shown two notches, affording thereby two adjustments for each lateral edge. The plate is also provided with notches on each of its curved ends, and these notches are adapted to engage with the pins 22, thus affording a further means of retaining the plate 17 in proper position. The pins 22, as shown, are screwed into the intermediate curved bearing portion 14.

By the means above described I am thus enabled to quickly and readily adjust the toe and heel points as desired, and in providing the intermediate series of points in the form of a semicylindrical transversely grooved or corrugated plate I obtain the additional advantage of the spring-cushion tread. The end screw-points serve to protect and supplement the intermediate points, thereby making a firm, substantial, and sharp footing for a horse on slippery pavements and roads.

The said toe and heel points may be used separately or together, as may be found necessary.

What I claim as new, and desire to secure by Letters Patent, is—

- 5 1. A horseshoe having the usual toe-calk; and tapped heel-calks provided with adjustable screw-points fitting said taps and extending through said shoe and outside of the hoof whereby the heel-points may be readily lengthened by the driver to make horse sharp.
- 10 2. A horseshoe having a toe-calk provided with adjustable points; and tapped heel-calks provided with adjustable screw-points fitting said taps and extending through said shoe, and outside of the hoof whereby said toe and heel points may be readily lengthened by driver to make horse sharp.
- 15 3. A horseshoe provided with tapped toe and heel calks; and adjustable screw-points fitting said taps and extending through said shoe at an angle to conform with the hoof, thus providing for wear and affording an easy means of adjustment.
- 20 4. A horseshoe having a toe-calk provided with adjustable points affording a spring-cushion tread and tapped heel-calks provided with adjustable points extending through said shoe.
- 25 5. A horseshoe provided with tapped toe-calks; adjustable screw-points fitting said taps, and an adjustable series of intermediate

points affording a spring-cushion tread; and tapped heel-calks provided with adjustable 35 points.

6. A horseshoe having a toe-calk provided with adjustable end screw-points protecting and supplementing an adjustable series of intermediate points; and adjustable heel- 40 points.

7. A horseshoe having a toe-calk provided with adjustable end screw-points protecting and supplementing an adjustable series of intermediate points acting as a spring-cushion 45 tread; and adjustable heel-points.

8. A horseshoe having a toe-calk provided with adjustable end screw-points protecting and supplementing an adjustable series of intermediate points on the lateral edge of a 50 semicylindrical transversely grooved or corrugated plate; and adjustable heel-points.

9. A horseshoe having a toe-calk provided with adjustable end screw-points protecting and supplementing an adjustable series of 55 intermediate points on the lateral edge of a semicylindrical transversely grooved or corrugated plate acting as a spring-cushion tread; and adjustable heel-points.

Signed at New York, in the county of New 60 York and State of New York, this 6th day of March, A. D. 1906.

FRANK W. LINDSLEY.
